Specification for Design.

Patented Nov. 2, 1915.

Application filed August 28, 1915. Serial No. 47,869. Term of patent 3½ years.

To all whom it may concern:

Be it known that I, HERMANN H. LOTT, a citizen of the United States, residing in the city of St. Louis, State of Missouri, have invented a certain new, original, and ornamental Design for Jewelry-Rings, of which the following is a specification, reference being had to the accompanying drawing, forming a part thereof, in which—

Figure 1 is a plan view of a jewelry ring embodying my new design; and Figs. 2, 3, and 4 are, respectively, side elevational, end elevational, and inverted plan views of the same.

I claim—

The ornamental design for a jewelry ring substantially as shown.

HERMANN H. LOTT.
